UNITED STATES PATENT OFFICE.

JOSEPH HUEFNER, OF BUFFALO, NEW YORK, ASSIGNOR TO CITY DAIRIES COMPANY, OF ST. LOUIS, MISSOURI, A CORPORATION OF INDIANA.

DESIGN FOR AN ADVERTISING SIGN.

Application filed March 17, 1928. Serial No. 25,897. Term of patent 14 years.

To all whom it may concern:

Be it known that I, JOSEPH HUEFNER, a citizen of the United States, residing at Buffalo, county of Erie, State of New York, have invented a new, original, and ornamental Design for Advertising Signs, of which the following is a specification, reference being had to the accompanying drawing, forming part thereof.

I claim:

The ornamental design for an advertising sign, as shown.

JOSEPH HUEFNER.
